(57) **CLAIM**

I claim the ornamental design for a high velocity fan and heater, as shown and described.

DESCRIPTION

FIG. 1 is a perspective view of the device of the present invention.

FIG. 2 is a front elevational view of the device of the present invention.

FIG. 3 is a right side elevational view of the device of the present invention.

FIG. 4 is a left side elevational view of the device of the present invention.

FIG. 5 is a rear elevational view of the device of the present invention.

FIG. 6 is a top view of the device of the present invention; and,

FIG. 7 is a bottom view of the device of the present invention.
